TRIMMING MECHANISM FOR SEWING MACHINES

John P. Weis, Nyack, N. Y., assignor to Metropolitan Sewing Machine Corporation, Nyack, N. Y., a corporation of Delaware

Application February 13, 1934, Serial No. 711,003

40 Claims. (Cl. 112—124)

This invention relates to trimming mechanism for sewing machines and more particularly to that form of trimming mechanism wherein the pinking and seaming of the work may be accomplished simultaneously, the object of the invention being to provide a pinking and trimming mechanism and an improved method by means of which a French felled seam may be produced simultaneously with the pinking of the free or raw edges thereof.

A further object of the invention is the provision of an improved rotary pinking or trimming means located below the working surface or cloth plate of the sewing machine over which the fabric passes during the stitching operation thereby not only leaving the work space entirely clear under the overhanging arm of the machine to permit the work to be freely handled but permitting also the stitching and trimming of a felled seam and, therefore, the trimming of the free edges of the work as it passes through the stitching mechanism.

A further object of the invention is the provision of an improved trimming or pinking mechanism so located under the cloth plate that it does not in any way interfere with or obstruct the use of the machine for ordinary plain stitching and by reason of its location is always in readiness for use either for plain work or for pinking and seaming without the removal of any parts.

A further object of the invention is the provision of a simple, inexpensive and efficient pinking mechanism readily applied to sewing machines as a permanent attachment thereto and so located as to avoid the necessity of detaching the same for plain stitching and which is also effective for making a felled seam and pinking the same.

Another object is the provision of an improved trimming or pinking mechanism adapted for use with the well known Metropolitan sewing machines and operated from the regular feeding mechanism thereby to permit the pinking cutter to work in unison or be synchronized with and be regulated by the adjustable means provided for changing the stroke of the feed dog thereby to vary the length of the stitch.

This improved rotary pinking trimmer is operative adjacent to and co-operates with the four-motion feed dog of such a sewing machine to trim the bottom ply of work, thus leaving the space free under the arm for the handling of the work above the cloth plate when it is desired to plain stitch the work.

In the drawing accompanying and forming a

part of this specification, Fig. 1 is a front view showing so much of the stitching and feeding mechanism of a well known Metropolitan sewing machine as is deemed necessary to illustrate the present improvement:

Fig. 2 is a detail, partly sectional view of this improved pinking mechanism applied to the machine:

Fig. 3 is a perspective partly sectional view of the improved pinking attachment and illustrates the manner of making the felled seam:

Fig. 4 is an end view of the sewing machine illustrated in Fig. 1, looking in the direction of the arrow in Fig. 1, and

Figs. 5 and 6 are detail views of the pinking element and the work guard for covering the exposed edge of the pinking cutter.

Similar characters of reference indicate corresponding parts in the several views.

Before explaining in detail the present improvement and mode of operation thereof, I desire to have it understood that the invention is not limited to the details of construction and arrangement of parts illustrated in the accompanying drawing since the invention is capable of other embodiments, and that the phraseology which I employ is for the purpose of description and not of limitation.

The sewing machine illustrated has the usual machine base 1 having a left hand bearing 2 for the main driving shaft 3. The rear end of the cloth plate 5 is supported by the lower portion 4 of the top arm, shown broken away, in the usual manner and the opposite end of the cloth plate is supported as at 6 by a projection 7 of the looper bracket 8, this looper bracket being secured to the base of the machine in the usual way and carrying the looper shaft 9 operating in bearings 10 and 11.

This looper bracket also has bearings 12, see Fig. 1, for the looper vibrating crank shaft 13 located transversely to the looper shaft 9 for imparting end-wise movement to the looper shaft 9 located in the bearings 10 and 11.

Rocking motion is imparted to the looper shaft 9 by an eccentric 14 secured to the main shaft 3 through the medium of a connection 15 operating on the eccentric and connected by a screw 16 to a crank arm 17 secured as at 18 to the looper shaft 9. By this means, movement is given to the looper carrier 19 and looper 20 so that it will coact with the needle 21 to make the stitch, the looper and the needle being threaded in the usual way. It is to be understood, however, that any of the well-known lock stitch mechanisms

5

20

30

45

50

55

may be used in place of the thread carrying looper 20 and the well-known vertical hook of lock stitch machines or the high speed rotary hook of the well-known Wilcox and Gibbs machine could be used in connection with the improved pinking and trimming mechanism herein shown and described.

The sewing machine illustrated herein has the usual top arm, not shown, terminating in a head, 10 the lower portion only of which is shown in Fig. 4 and which head carries the usual presser foot shank 23 and a compensating presser foot 24. This presser foot is made in several parts so as to yield and compensate for different thicknesses 15 of work. That is to say, if the character of work requires a seam composed of two or three thicknesses of material so that different portions of the work will be engaged by the presser foot, the sections 25 and 26 of the presser foot may be arranged to accommodate such varying thicknesses 20 in the work. These compensating presser feet are well known in the art, it being a mere matter of selection to provide suitable presser feet for seams of varying thicknesses and the sections of 25 the presser feet have independent pressure given to them by springs 27.

The main shaft 3 operating in the bearing 2 has an adjustable crank 28, see Fig. 4, operating 30 a connection 29 connected as at 30 to a top of a feed rocker frame 31 pivoted to the base of the machine as at 32 in the usual way. This rocker frame operates the feed bar 33 to impart movement to the four-motion feed dog 34 operating through the throat plate 35. This feed dog 35 operates at the left of and in front of the needle 21, see Fig. 3, and also extends in the rear of the needle and quite some distance to the right of the line of stitches made by the needle so as to act on the goods directly in back of the pinking 40 cutter. The right hand extension of the rear portion of the feed coacts with the section 25 of the compensating presser foot while the left hand section of the feed 34 coacts with the compensating section 26 of the presser foot, the needle 21 45 co-operating with the looper 20 to form the stitches, this needle passing through the needle hole 36 in the throat plate 35, the work being acted upon by the feed dog 34 so as to draw it from the stitching position as illustrated in 50 Fig. 3.

The cloth plate 5 is provided on the under side thereof with bearings 37 and 38, see Fig. 2, for the reception of a shaft 39 having secured thereto the rotary pinking cutter 40 shown of circular 55 or disk form having a continuous set of cutting teeth to pink the work and which is driven by this shaft and is adjustable to and from the stitch line with the shaft in the bearings 37 and 38.

The intermittent clutch 41 is secured to the 60 shaft by a screw 42, this clutch being located between the bearings 37 and 38 which thus prevents the shaft from shifting endwise except when the screw 42 is released and which thus permits lateral adjustment of the rotary trimming cutter when desired.

The clutch has an oscillating member 43 operated by a connection 44 which is loosely connected as at 45 to this oscillating member so as to give a step by step movement to the pinking cutter in 70 unison with the feed dog 34.

The opposite end of this connection or connector 44 is secured as at 45, see Fig. 4, to a segmental lever or member 46, likewise mounted on the pivot shaft 32 and is rocked back and forth 75 by a connection 47, one end of which is coupled

to the top end of the segmental lever 46 and the opposite end being connected with an eccentric mounted on the shaft 3 whereby a rocking motion is imparted to this segmental lever so as to operate the connection 44 and thereby the intermittent clutch to rotate the rotary pinking cutter.

By adjusting an end of the connection 44 to different positions on the segmental lever, the oscillating movement of the clutch member 43 is regulated to vary the stroke of the pinking cutter independently of the stroke of the feed dog and since the pinking cutter is very efficient in feeding the work it is often advantageous to give it a greater or less stroke on different kinds of work thereby to overcome stretching in some instances and at other times to cause the work to feed somewhat in a curved path to the right or left as the case may be which is an advantage in stitching curved or circular work.

There are many kinds of stitching operations 20 in which such a differential movement of the pinking cutter relative to the four-motion feed would not be required and in these operations the connecting link or connector 44 could be secured directly to the feed operating parts so that the 25 change in the stroke of the feed dog would also change the stroke of the pinking cutter, in which case, the segmental lever 46 would not be required.

Coacting with the pinking cutter 40 is a 30 hardened steel member 49 which overhangs the top surface of the cutting edge of the pinking cutter. This hardened member is slightly rounded upward at its front edge as at 50 to facilitate the passage of the work therebetween and the 35 cutter, and downward at its rear projecting edge as at 51 to facilitate the passage of that particular part of the work passing over the plate back to its normal position relative to the other portion of the work. The overhang or projection 40 of this member is made to suit variations in width of seam according to requirements.

To give pressure to this member against the cutting surface of the pinking cutter 40, an adjusting means in the form of a pin 52, see Fig. 3 45 is provided, this pin being located in a small recess in the top surface of the cloth plate 5 and is in alignment with the main driving shaft 3 and therefore at right angles to the line of stitching.

This pin supports the fixed cutting member or plate 49 which is a part of and projects from the left hand edge of a plate 56. The adjusting screw 54 holds this plate 56 securely to the cloth plate 5 at the rear of the pin 52 while two screws 55 hold the front edge of this plate in fixed relation to the cloth plate in front of the pin 52. This pin 52 forms a rocking member upon which the plate 56 rests and rocks and by reason of the adjusting screws, it may be tipped toward or from the pinking cutter 40 and located in such position by the tightening of the screws 54 and 55 and as the pin 52 is seated in the cloth plate and also in a recess in the plate 56 carrying the cutting member 49, this affords one way of securing that cutting member 49 in an adjustable manner with relation to the rotary cutter 40. In other words, this pin 52 provides sufficient space between the top surface of the cloth plate 5 and the bottom surface of the plate 56 to permit adjustment 60 of the plate 56 and the rigid or stationary hardened plate 49 in the manner just described and the space thus provided between the cloth plate and the hardened steel portion 49 of the plate 56 65 would provide in part accommodation for the 70

75

range of work for which the machine is to be used. That is to say, if the cutter 40 projected over the cloth plate one-eighth of an inch and the cutting member 49 were brought into contact with the cutter, goods equal to the thickness of approximately one-eighth of an inch would pass through the machine freely.

To accommodate seams and other obstructions, this space would have to be three-sixteenths or one-fourth of an inch as the case may be, the object, however, being to confine this space, especially for thin delicate silk fabrics so that portions of a garment being seamed may be fed over the top of the plate 56 with the least possible resistance.

When the machine is equipped for heavier work and greater space is required for the seams to pass through, the adjustment of the plate 56 would elevate it sufficiently to accommodate such extra thicknesses.

Secured to the front edge of the plate 56 is a shank 57 of a work guide 58 which has a projecting end 59, see Fig. 3, located in line with the line of stitches and positioned very close to the front of the needle hole 36. This guide has elongated slots and may be adjusted by means of the screws 60 and 61 so as to properly control the folded edge 62 of the goods or work 63 folded around this guide, the free edge 65 of the work being pinked by the cutter 40.

This free edge 65 is fed in under the guide 58 and on top of the free edge 66 of the fabric 67. In other words, the two pieces of fabric, the right hand piece 63 and the left hand piece 67 are fed together over the top of the cloth plate with the inner edge of the fabric 63 folded under and around the guide 58 on top of the projecting edge of the fabric 67, the two pieces of fabric being stitched by the stitching mechanism to form the seam. These lapping edges of the fabric to be pinked will pass under the hardened steel portion of the plate 56 and between it and the rotary trimming cutter 40 and thus pinked.

It will be obvious that by adjusting the screws 60 and 61 of the folder guide 58, the proper fold 62 will be made in the edge of the right hand piece of fabric 63, thus forming a felled seam. This folder guide is adjustable to control the margin from the stitch line. Thus, by means of this improved trimming mechanism, a French felled seam can be simultaneously made and pinked from the under side since the free projecting edges 65 and 66 of the two layers of material may be readily pinked without pinking through the overlapping top layer 63 of the work by reason of the means hereinbefore referred to that separates such projecting or free edges from the overlapping portion of the material.

When the machine is to be used for plain or ordinary stitching and no trimming is required, a suitable guard 68, see Figs. 5 and 6 is adjustable in the manner shown in Fig. 6 so that the guard will contact with the edge 59 of the hardened plate 48 and thus cause the work to feed up over the member 49 instead of thereunder and prevent it from getting into cutting position between the hardened member 49 and the rotary cutter 40.

When it is desired to pink the work, the screw 69 is loosened and the guard shifted to the position shown in Fig. 5 thereby permitting the edge to be pinked to be fed between the hardened plate 49 and the cutter 40.

This guard has a collar 10 which fits over the hub 11 of the bearing 37 and the semi-circular portion 12 of the guard guards the cutting sur-

face of the cutter and protects the fingers of the operator, and thus it will be seen that this guard serves two purposes in that it at all times protects the operator from injury by the cutter 40 and is adjustable to close the opening between the cutting members when adjusted as shown in Fig. 6 and enables the machine to be used for plain seaming operations.

5

From the foregoing, it will be seen that I have provided an improved trimming mechanism which is always in position and out of the way under the cloth plate, thereby providing a clear space for the work under the arm and which, by reason of its location, is effective to trim those plies of a piece of work having free edges and which trimming mechanism is effective to permit plain work or pinking work without the detachment or attachment thereof or the removal or replacement of any parts.

It is to be understood that, by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A trimming attachment adapted for use with a sewing machine and comprising a rotary disk shaped trimmer, means for rotating it, and a stationary hardened surface located above the rotary trimmer and co-operating therewith.

2. A trimming attachment adapted for use with a sewing machine and comprising a rotary disk shaped trimmer, means for rotating it, and a stationary hardened adjustable surface located above the rotary trimmer and co-operating therewith.

3. A trimming attachment adapted for use with a sewing machine having stitching mechanism including a needle and comprising a rotary trimmer, means for operating it, a stationary hardened surface located above the rotary trimmer and co-operating therewith, and means for adjusting the trimmer toward and from the needle.

4. A trimming attachment adapted for use with a sewing machine having stitching mechanism including a needle and comprising a rotary trimmer, means for operating it, a stationary hardened surface located above the rotary trimmer and co-operating therewith, means for adjusting the trimmer toward and from the needle, and means for adjusting the hardened surface toward and from the trimmer.

5. In a sewing machine having a cloth plate, a rotary disk shaped trimmer located below said cloth plate, a rigid co-operating surface above said plate, and means for operating the rotary trimmer.

6. In a sewing machine having a cloth plate, a rotary trimmer located below said cloth plate, a rigid co-operating surface above said plate, and eccentric means for operating the rotary trimmer.

7. In a sewing machine having a cloth plate, a rotary disk shaped trimmer located below said cloth plate, a rigid co-operating surface above said plate, feeding mechanism, and means operative simultaneously with the feeding mechanism for operating said trimmer.

8. In a sewing machine having a cloth plate, a rotary trimmer located below said cloth plate,

- a rigid co-operating surface above said plate, means for operating the rotary trimmer, and means for regulating the speed of the rotary trimmer.
5. 9. In a sewing machine having a cloth plate, a rotary trimmer located below said cloth plate, a rigid co-operating surface above said plate, means for operating the rotary trimmer, feeding mechanism, and means connected with the feed mechanism for regulating the speed of the rotary trimmer.
10. 10. In a sewing machine having a cloth plate, a rotary trimmer located below said cloth plate, a rigid co-operating surface above said plate, means for operating the rotary trimmer, and oscillating means for regulating the feed of the rotary trimmer.
15. 11. In a sewing machine having a cloth plate, a rotary trimmer located below said cloth plate, a rigid co-operating surface above said plate, eccentrically operated means for operating the trimmer, and means for regulating the speed thereof.
20. 12. A sewing machine having a cloth plate, a rotary pinking trimmer supported below said plate and projecting therethrough, and means for rotating it.
25. 13. A trimming attachment for sewing machines having a cloth plate and comprising a rotary disk shaped trimmer supported under and projecting through said plate, means for rotating it, a stationary rigidly supported co-operating hardened member located above said plate, and means for rigidly supporting the rotary trimmer in position to co-operate with said member.
30. 14. A trimming attachment for sewing machines having a cloth plate and comprising a rotary trimmer supported under and projecting through said plate, means for rotating it, a stationary rigidly supported co-operating hardened member located above said plate, means for rigidly supporting the rotary trimmer in position to co-operate with said member, and means for adjusting said hardened member toward and from the rotary trimmer.
35. 15. A trimming attachment for sewing machines having stitching means and comprising a rotary pinking trimmer, means for rotating it, and means co-operating therewith, said rotary trimmer and its co-operating means being so located as to pink the bottom plys of a felled seam during the stitching thereof.
40. 16. A trimming attachment for sewing machines having stitching means and comprising a rotary pinking trimmer, means for rotating it, means co-operating therewith, said rotary trimmer and its co-operating means being so located as to pink the bottom plys of a felled seam during the stitching thereof, and means operative to feed a part of the work between the trimming members and a part thereof over the co-operating member.
45. 17. A trimming attachment for sewing machines having stitching means and comprising a rotary pinking trimmer, means for rotating it, means co-operating therewith, said rotary trimmer and its co-operating means being so located as to pink the bottom plys of a felled seam during the stitching thereof, and means operative to feed a part of the work between the trimming members and a part thereof over the co-operating means, said means comprising a guide adjustable relative to the co-operating means.
50. 18. A trimming mechanism for sewing ma-
- chines comprising a rotary cutter, means for rotating it, a stationary rigidly supported co-operating hardened plate located above said rotary cutter, and means for regulating the pressure of said plate relative to the rotary cutter.
55. 19. A trimming mechanism for sewing machines comprising a rotary cutter, means for rotating it, a stationary rigidly supported co-operating hardened plate located above said rotary cutter, and means for regulating the pressure of said plate relative to the rotary cutter and including means for supporting said plate for rocking movement.
60. 20. A trimming mechanism for sewing machines having a cloth plate and comprising a rotary trimmer supported below the cloth plate, means for rotating it, a stationary rigidly supported co-operating hardened member located above the cloth plate, and an adjustable protecting guard adjustable into position to guide the folded edge of the work between the cutting members or thereabove.
65. 21. A sewing machine having a cloth plate, a disk shaped rotary cutter projecting through the plate from the under side thereof, means for rotating it, and means for varying the speed thereof.
70. 22. A sewing machine having a cloth plate, a disk shaped rotary cutter projecting through the plate from the under side thereof, means for rotating it intermittently, and means for varying the speed thereof.
75. 23. A sewing machine having a cloth plate, a disk shaped rotary cutter projecting through the plate from the under side thereof, feed mechanism, and means for operating the cutter coincident with the feed mechanism.
80. 24. A sewing machine having a cloth plate, a disk shaped rotary cutter projecting through the plate from the under side thereof, feed mechanism, and means for operating the cutter coincident with the feed mechanism and including means for varying the speed thereof.
85. 25. A sewing machine having a disk shaped rotary cutter, means for rotating it, a fixed member co-operating therewith, and a shiftable member to guide the work between said members or over the fixed member.
90. 26. A sewing machine having a disk shaped rotary cutter, means for rotating it, a fixed member co-operating therewith, and a shiftable member to guide the work between said members or over the fixed member and comprising a guard for the cutter.
95. 27. A sewing machine having a disk shaped rotary cutter, means for rotating it, a fixed member co-operating therewith, and a shiftable member to guide the work between said members or over the fixed member and comprising a guard for the cutter and means for securing it in any of its adjusted positions.
100. 28. A sewing machine having a cloth plate, a driving shaft, a shaft located below the cloth plate, a disk shaped rotary pinking cutter carried by said last shaft and projecting through the plate, means connected with the driving shaft for operating the cutter, and rigid means located above the cutter for co-operation therewith.
105. 29. A sewing machine having a cloth plate, a driving shaft, a shaft located below the cloth plate, a disk shaped rotary cutter carried by said last shaft and projecting through the plate, means connected with the driving shaft for operating the cutter, rigid means located above the cutter, rigid means located above the cutter, and means for supporting the cutter for rocking movement.

the cutter for co-operation therewith, and means for regulating the speed of the cutter.

30. A sewing machine having a cloth plate, a driving shaft, a shaft located below the cloth plate, a disk shaped rotary cutter carried by said last shaft and projecting through the plate, eccentric means connected with the driving shaft for operating the cutter, rigid means located above the cutter for co-operation therewith, and means for regulating the speed of the cutter.

31. A sewing machine having a cloth plate, a driving shaft, a shaft located below the plate, a disk shaped rotary pinking cutter carried by said last shaft and projecting through the plate, feed mechanism, means connected with the driving shaft for operating the feed mechanism, means also connected with the driving shaft for rotating the cutter, and fixed means located above the cutter and co-operating therewith.

32. A sewing machine having a cloth plate, a driving shaft, a shaft located below the plate, a disk shaped rotary cutter carried by said last shaft and projecting through the plate, feed mechanism, means connected with the driving shaft for operating the feed mechanism, means also connected with the driving shaft for rotating the cutter, fixed means located above the cutter and co-operating therewith, and means for regulating the speed of the cutter according to the speed of the feed mechanism.

33. A sewing machine having a cloth plate, a driving shaft, a shaft located below the cloth plate, a rotary cutter carried by said last shaft and projecting through the plate, a four-motion feed mechanism, a shaft supporting said four-motion feed mechanism, means connecting said feed shaft with the driving shaft for operating the feed mechanism, means also connecting said feed shaft with the driving shaft for intermittently rotating the cutter, and means located above the cutter and co-operating therewith.

34. The method of forming a felled seam which consists in hemming one layer of fabric and stitching the hemmed edge thereof to another layer of fabric along the top of the hemmed portion thereby to provide juxtaposed portions of said fabrics projecting beyond the stitch line, and simultaneously pinking the projecting edges from below the layer having the hemmed edge by a rotary pinking movement.

35. The method of forming a seam which consists in stitching a plurality of plies of material

together to form a seam having one or more free edges and simultaneously with such stitching, pinking the free edge portions of the fabric from the under side of such fabric by a rotary pinking movement without pinking an overlapping top layer of the work.

36. The method of forming a seam which consists in stitching a plurality of plies of material together to form a seam having one or more free edges and simultaneously with such stitching 10 pinking the free edge portions of the fabric while lying in the normal horizontal plane of the material being stitched from the under side of such fabric without pinking an overlapping top layer 15 of the work.

37. The method of forming a felled seam which consists in hemming one layer of fabric and stitching the hemmed edge thereof to another layer of fabric along the top of the hemmed portion thereby to provide juxtaposed portions of 20 said fabrics projecting beyond the stitch line, and simultaneously pinking the projecting edges while lying in the normal horizontal plane of the material being stitched from below the layer having the hemmed edge without pinking an overlapping top layer of the work.

38. The method of forming a seam which consists in stitching a plurality of plies of material together to form a seam having one or more free edges and simultaneously with such stitching 30 feeding the work between a hardened stationary surface and a movable pinking surface to effect the pinking of the work while lying in the normal horizontal plane of the material being stitched.

39. The method of forming a seam which consists in stitching a plurality of plies of material together to form a seam having one or more free edges and simultaneously with such stitching feeding the work between a hardened stationary 35 surface and a movable pinking surface below 40 said stationary surface to effect pinking of the work from the under side thereof.

40. The method of forming a seam which consists in stitching a plurality of plies of material together to form a seam having one or more free 45 edges and simultaneously with such stitching feeding the work between a hardened stationary surface and a rotary pinking surface synchronized with the feeding of the work to effect the pinking of such work.

JOHN P. WEIS.
